(57) **CLAIM**

I claim the ornamental design for a lighting fixture, as shown and described.

DESCRIPTION

FIG. 1 is a front perspective view of the lighting fixture showing a first embodiment of the new design with the fixture having a five-way (72°) overall rotational symmetry and the overall shape of the glass pieces being rotationally symmetrical; and,

FIG. 2 is a front perspective view thereof showing a second embodiment of the new design with the fixture having a three-way (120°) overall rotational symmetry (the six lower arms, supports, and glass pieces having a six-way (120°) overall symmetry) and the overall shape of the glass pieces being rotationally symmetrical.
